UNITED STATES PATENT OFFICE.

JOSEPH E. FISK, OF SALEM, MASSACHUSETTS.

IMPROVEMENT IN DRY GAS-METERS.

Specification forming part of Letters Patent No. 39,907, dated September 15, 1863; antedated February 13, 1863.

To all whom it may concern:

Be it known that I, JOSEPH E. FISK, of Salem, in the county of Essex and State of Massachusetts, have invented a new and useful Improvement in Operation of Valves of Gas-Meters; and I do hereby declare that the following is a full, clear, and exact description thereof, reference being had to the accompanying drawings, forming part of this specification, in which—

Figure 1 is a vertical longitudinal section of a gas-meter with my improvement applied to it. Fig. 2 is a horizontal section through the register-gear chamber. Fig. 3 is a plan of the valve within the gas-chest and on its seat. Fig. 4 is a vertical section of Fig. 3. Fig. 5 is an under side view of the valve. Figs. 6 and 7 are upper and under side views of the seat. Figs. 8, 9, 10, 11, and 12 are views of modifications of the invention.

The same letters of reference in the several figures indicate like parts.

The nature of my invention consists in a gas-meter valve which, while operating over the ports of its seat, is so controlled that all of its sides maintain a parallelism with the sides of the several ports of the seat, and at the same time every part of the working surface of the valve describes small circles the radii of which are equal to the radius of the eccentric or crank which produces the motion in the valve, said radius being about equal to the width of the ports. Thus every part of the working surface of the valve-seat is traversed and worn equally.

It consists, second, in the combination, with the eccentric or crank, of the annular cross and open guides, the same being one means for controlling the eccentric motions of the valve.

It consists, third, in so disposing the gas-ports of the valve-seat that they inclose a central discharge-passage, in combination with a valve constructed with a rim on its under side, whereby the sediment which collects on the valve-seat is scraped off and discharged into the central passage, and also the influx and efflux of the gas take place, on opposite sides of the center of the valve-seat, simultaneously.

To enable others skilled in the art to make and use my invention, I will proceed to describe its construction and operation.

The operation of the diaphragms of the meter which is represented in the drawings is the same as that of many meters in use—that is, the gas alternately presses against opposite sides of each diaphragm, and while the gas is entering the space or chamber on one side of a diaphragm it is passing out of the chamber on the opposite side.

A is a valve-seat, of hexagon shape, and with six gas-ports, $a' a'' a''' a'''' a'''''$, through it, said ports being arranged round a central hexagon shaped discharge-orifice, b, which terminates in a circle and connects with the outlet B of the gas-meter. At one side of the seat, and outside of the binding-line of the working-surface thereof, a right-angle inlet-passage, C, is formed, said passage leading horizontally and vertically through the seat into a gas-chest, D. This valve-seat is arranged in the center of the partition E, which divides the diaphragm-chambers $F F' F'' F''' F'''' F'''''$ from the registering-gearing chamber G, and its ports leading into the diaphragm-chambers—that is, three by means of curved directors $I I' I''$ and three by means of pipes $I''' I''' I'''$.

J is a hexagon-shaped valve, with a rim, J', projecting from its under surface, said rim inclosing a hexagon-shaped chamber, J'', of an area in any direction sufficient to inclose the whole of one port, about two thirds of another, and about one-third of another, while one of the remaining three ports is wholly open to the inflowing gas, another about two-thirds open, and another about one-third open. The width of the rim of the valve is sufficient to cover the ports of the seat with a slight lap. The top of the valve has an open guide, K K', at two of its corners, said corners being diametrically opposite one another, and in the center of the back of the valve is formed a circular socket, d, for a crank-pin to set in.

D is a gas-chest, of hexagon shape, and with a permanently fitted top. At opposite ends, and from the base of this chest, ears e e project horizontally, said ears resting upon extensions of the valve-seat, and being fastened thereto by means of screws f f. From opposite ends of the chest, on the inside, and at right angles to the guides K K', other open guides, M M, project a short distance, and from the center of the top of the chest a vertical stuffing-box, N, extends upward, said stuffing-box

leading out of the gas-chamber of the chest. In the guides K K and M M a cross, O, is fitted loosely, the arms of said cross terminating in a central ring, and being shorter than the guides. Down through the stuffing box and the ring of the cross a shaft, P, with a crank or eccentric, h, at its lower end, and a crank, g, at its upper end, extends; the pin i of the eccentric h entering the socket d in the center of the back of the valve, and the pin j of the crank g passing through the inner ends of the connecting-arms Q Q Q of the diaphragms.

From the foregoing description it will be evident that if the valve occupies the position shown in Figs. 1 and 3 the gas will, when "let on," flow into the gas-chest through the passage O, and therefrom through the ports a a' a'', pass into three of the diaphragm-chambers—that is, to the full capacity of the port a, about two-thirds the capacity of the port a', and about one-third the capacity of the port a''—and thus, through the motion imparted to the diaphragms and the intermediate connections, set the valve in operation. The valve, being set in motion in the direction of the arrow 1, is caused to perform, by the crank or eccentric, an eccentric movement over the ports of the seat, and in making its movements every part of its working-surface describes small circles, the radii of which are equal to the radius of the crank or eccentric, which radius is about equal to the width of the ports, and thus, as the working-surface of the valve is a rim, and said rim incloses a chamber in the valve and the discharge-orifice of the seat, every part of the working-surface of the valve and seat will, while of necessity wearing equally, be kept clean of sediment, &c., the sedimentary deposits being swept by the motions of the valve into the discharge-orifice of the seat. In the motions of the valve, it is prevented from turning out of proper relation to the ports by means of the cross O and the guides K K and M M, and the ports a a' a'' a'' a'' are successively opened fully to the inflowing gas; but when the port a is fully open to the inflowing gas and introducing the gas into the outer diaphragm-chamber F the port a'' is fully open to the outflowing gas of the inner diaphragm-chamber F', and when port a' is open to the inflowing gas and introducing the same into the inner diaphragm-chamber F' port a'' is open to the outflowing gas of the outer diaphragm-chamber F'', and when port a'' is open to the inflowing gas and introducing gas into the outer diaphragm-chamber F'' port a'' is open to the outflowing gas of one of the inner diaphragm-chambers F'', and vice versa, as respects the entrance and exit of the gas to and from the diaphragm-chambers when the ports a'' a'' a'' are fully open to the inflowing gas. The gas, of course, in discharging from the diaphragm-chamber circulates in the chamber in the under surface of the valve and then descends through the central discharge-orifice and passes off through the pipe B, as indicated by the arrows 2 and 3.

In Figs. 8 and 9 means differing from the cross O and guides K M are shown for keeping the sides of the valve parallel to the sides of the seat while its surface is performing an eccentric movement over the ports of the seat and every part of its working-surface describing small circles. In this modification it will be seen that the seat of the valve is square and the gas-ports differently disposed from what they are in Figs. 6 and 7; also, that the valve is moved from its under side by means of an eccentric, the crank-rod of which is to extend down through a central tube of a gas-meter and connect with diaphragms in a proper manner by means of its lower eccentric or crank. The motions of the valve transversely and longitudinally are maintained by means of a T-shaped guide-rod, R S, which slides longitudinally with the valve, while the valve slides transversely on it.

In Figs. 10 and 11 means differing from both the cross and the T-shaped bar are shown for maintaining the parallelism of the sides of the valve with the sides of the ports while every part of its working-surface is describing small circles. It will be observed that the disposition of the ports of the seat is different from that of either of the other plans referred to, but that the eccentric is applied in the same manner as in Figs. 8 and 9. There is provided to maintain the specified motions of the valve a sliding yoke, U, which fits around a central hub, u, on the under side of the valve, and presenting two stops, v v, which play in longitudinal slots of the valve-seat as the valve performs its movements.

I have shown and described several forms and constructions of valves and seats and modes of arranging the same; but, under the first clause of my claim, I do not limit myself to any particular form or construction or mode of arranging the valve and seats, nor to any particular means for producing the motions of the valve, but intend to cover, broadly, the combination of the motions, in a gas-valve, which are specified in the first clause of the statement of the nature of the invention.

What I claim as my invention, and desire to secure by Letters Patent, is—

1. The combination of a rotary crank or eccentric and guides and stops K K M M O, substantially as and for the purpose set forth.

2. The arrangement of the chambered valve, which is operated with an eccentric motion, and controlled by a cross or its equivalent, as described, in said motion, in combination with the gas-ports arranged on opposite sides of the seat and around a central discharge-passage, in the manner and for the purposes herein described.

Witness my hand, in the matter of my improved valve for dry gas-meters, this 28th day of December, A. D. 1861.

JOSEPH E. FISK.
